UNITED STATES PATENT OFFICE.

HENRY E. BRUNHOFF, OF CINCINNATI, OHIO, ASSIGNOR TO THE BRUNHOFF MANUFACTURING COMPANY, OF CINCINNATI, OHIO, A CORPORATION OF OHIO.

DETACHABLE LID.

Application filed December 17, 1923. Serial No. 681,038.

My invention relates to improvements in containers. One of its objects is to provide a detachable hinged lid for containers to enable the original containers to be used for vending purposes, and the hinged lids to be transferred from one original container to another as the goods from one container after another are disposed of and removed. Another object is to provide improved means to detachably connect a hinged lid to the original container. Another object is to provide for a close and practically moisture and dust proof connection between the hinged lid and the original container. Another object is to provide a hinged lid of transparent material through which the goods in the original package may be displayed and at the same time kept clean and in good salable condition. My invention also comprises certain details of form, and combination and arrangement of components, all of which will be fully set forth in the description of the accompanying drawings, in which:

Fig. 1 is a central vertical section through an original container and its original or shipping lid.

Fig. 2 is a top plan view of the same with the original lid detached and replaced by a transparent hinged lid detachably attached to said original package.

Fig. 3 is an enlarged sectional detail taken on line 3—3 of Fig. 2.

Fig. 4 is a side elevation of the original container with its hinged lid in the open position.

Fig. 5 is an enlarged perspective view of the separated members by means of which the hinged lid is hinged and detachably connected to the original package.

The accompanying drawings illustrate the preferred embodiment of my invention in which 15 represents a type of original sheet metal package quite extensively employed in different sizes for the packing and shipment of a variety of articles of commerce, as for instance cakes, candies and groceries. The goods are usually adapted to be conveniently vended directly from the original package, and the original or shipping cover of sheet metal 16 being closely fitted to the opening 17 in the top of the original package is not adapted either to displaying the goods within the original package, or to be readily detached from or applied to the original package. The lid 16 is forced or wedged tightly

into place in the opening, and hence is not readily detachable.

I therefore have provided a hinge member 20 having hinge eyes 21 and 22, which hinge member is also provided with a finger or hook 24 adapted to enter the opening 17 of the original package and to hook over the inwardly turned annular edge 25 of the sheet metal at the opening 17, to hold the hinge member 20 in place with reference to the original package. The sheet metal of the hinge member 20 is also folded upon itself at 26 to embrace opposite faces of the annular sheet metal seam 27 of the original package to serve as an additional locking means to detachably lock the hinge member 20 to the original package near the mouth thereof. The locking members 24 and 26 act mutually to firmly and detachably hold the hinge member 20 in place with reference to the original package, and at the same time enable said hinge member 20 to be readily detached from one original package and applied to another similar original package. An upwardly projecting member 28, preferably formed integrally with the hinge member 20 serves as a stop or rest against the upper end of which the hinged lid is designed to rest and be supported when the lid is in its open position as shown in Fig. 4. I also preferably stamp up a tongue 30 from the member 28, as shown in Fig. 5, which tongue is designed to serve as a resilient finger to hold a price tag in place with reference to the member 28, by slipping the price tag between the finger 30 and the member 28.

A lid 32 preferably composed of a panel 33 of glass or other transparent material and an annular metal binding member 34 having a recess or channel to be fitted over the edge of the panel 33, and an inwardly turned annular flange 35, designed to fit into the open mouth 17 of the original package and to thereby make a sufficiently close joint with the inwardly turned flange 25 of the original package to provide a practically dust proof and moisture excluding or including joint between the hinged lid and the mouth of the original package, and at the same time said lid being readily lifted from and applied to the mouth of the original package as may be required.

The metal member 34 is provided with one or more hinge eyes preferably formed by soldering or brazing two short sections of

brass tubing 37 and 38 to the meeting ends of the metal member 34, whereby the member 34 may be applied to the rim of the panel 33 and the hinge eyes 37 and 38 brought together and interposed between the hinge eyes 21 and 22 and locked in place upon the panel 33 and also with reference to the hinge member 20 by means of a hinge rod 40. The hinged lid and hinge member 20 are thus 10 adapted to be successively applied to and removed from successive original packages and used therewith while vending the contents of the successive original packages, thus serving to display the goods within the original package, to give ready access to the interior of the original package and to afford a practically moisture and dust proof joint when the lid is in its closed position. A lifting member 42 enables the lid to be conveniently lifted and closed.

The apparatus herein shown and described is capable of considerable modification within the scope of the claims without departing from the spirit of my invention.

25 What I claim is:

1. A detachable hinge supporting member adapted to be applied to the top of a can having a rim and an inwardly extending ledge, said hinge supporting member comprising a hook-like member adapted to engage over the inner edge of the can ledge, a plate adapted to rest upon the can ledge, and a recessed member adapted to engage over the can rim, the parts having such resiliency and the recessed member being so related to the hook member that when the hook member is in engagement with the inner edge of the can ledge, the recessed member may be snapped on and off from the can rim.

2. A detachable cover adapted to be applied to the top of a can having a rim and an inwardly extending ledge, comprising a can lid and a hinge supporting member hinged to said lid, said hinge supporting member comprising a hook-like member adapted to engage over the inner edge of the can ledge, a plate adapted to rest upon the can ledge, and a recessed member adapted to engage over the can rim, the parts having such resiliency and the recessed member being so related to the hook member that when the hook member is in engagement with the inner edge of the can ledge, the recessed member may be snapped on and off from the can rim.

3. A detachable hinge supporting mem-

ber adapted to be applied to the top of a can having a rim and an inwardly extending ledge, said hinge supporting member comprising a hook-like member adapted to engage over the inner edge of the can ledge, a plate adapted to rest upon the can ledge, a recessed member adapted to engage over the can rim, and an upwardly extending member adapted to support a can lid in its inclined open position, the hook member plate member and recessed member having such resiliency and the recessed member being so related to the hook member that when the hook member is in engagement with the inner edge of the can ledge, the recessed member may be snapped on and off from the can lid.

4. A cover adapted to be detachably applied to the top of a can having a rim and an inwardly extending ledge, comprising a can lid and a hinge supporting member hinged thereto, said hinge supporting member comprising a hook-like member adapted to engage over the inner edge of the can ledge, a plate adapted to rest upon the can ledge, a recessed member adapted to engage over the can rim, and a lid supporting member projecting upwardly and adapted to support the lid in an inclined open position, the hook member plate member and recessed member having such resiliency and the recessed member being so related to the hook member that when the hook member is in engagement with the inner edge of the can ledge, the recessed member may be snapped on and off from the can rim.

5. A cover adapted to be detachably applied to the top of a can having a rim and an inwardly extending ledge said cover comprising a can lid having an inwardly turned annular flange to fit into the can opening and a hinge supporting member hinged to said can lid, said hinge supporting member comprising a hook-like member adapted to engage over the inner edge of the can ledge, a plate adapted to rest upon the can ledge, and a recessed member adapted to engage over the can rim, the parts having such resiliency and the recessed member being so related to the hook member that when the hook member is in engagement with the inner edge of the can ledge the recessed member may be snapped on and off from the can rim.

In testimony whereof, I have hereunto affixed my signature.

HENRY E. BRUNHOFF.
